US0D1052064S

(12) **United States Design Patent** (10) **Patent No.:** **US D1,052,064 S**
(45) **Date of Patent:** **** Nov. 19, 2024**

(54) **AROMATHERAPY SPRINKLER**

(71) Applicant: **Kaien Qi**, Guangzhou (CN)

(72) Inventor: **Kaien Qi**, Guangzhou (CN)

(73) Assignee: **Kaien Qi**, Guangzhou (CN)

(**) Term: **15 Years**

(21) Appl. No.: **29/931,056**

(22) Filed: **Mar. 5, 2024**

(51) **LOC (14) Cl.** **23-01**

(52) **U.S. Cl.**

CLAIM

The ornamental design for an aromatherapy sprinkler as shown and described.

DESCRIPTION

FIG. 1 is a front perspective view of an aromatherapy sprinkler showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a plan view thereof;

FIG. 8 is a bottom view thereof; and,

FIG. 9 is an exploded view thereof.

The broken lines in the drawings depict portions of the aromatherapy sprinkler that form no part of the claimed design.

1 Claim, 9 Drawing Sheets
